DESIGN FOR A LAWN MOWER

Robert H. Ensign, New York, N. Y., assignor to
John A. Roebling's Sons Company, Trenton,
N. J., a corporation of New Jersey

Application November 14, 1946, Serial No. 134,775

Term of patent 14 years

(Cl. D40—1)

To all whom it may concern:

Be it known that I, Robert H. Ensign, a citizen of the United States, residing in New York city, county and State of New York, have invented a new, original, and ornamental Design for a Lawn Mower, of which the following is a specification, reference being had to the accompanying drawing, forming a part thereof, in which

Figure 1 is a perspective view of the lawn mower showing my new design complete with motor and front and rear covers; and

Figure 2 is a similar view of the frame with the motor, driving mechanism and covers removed.

The characteristic features of my design are those shown in full lines in the drawing.

I claim:

The ornamental design for a lawn mower, as shown and described.

ROBERT H. ENSIGN.
